CABLE SUPPORT

Charles H. Klein, Cleveland, Ohio, assignor to
The National Telephone Supply Company,
Cleveland, Ohio, a corporation of Ohio

Application December 14, 1938, Serial No. 245,685

2 Claims. (Cl. 248—61)

This invention relates, as indicated, to cable supports, but has reference more particularly to saddles for such supports.

In Brenizer Patents Nos. 1,698,531 and 5 1,705,233, there are disclosed cable hangers provided with cable supporting saddles, which present broad areas of supporting surface for the cable. These saddles are designed to prevent cutting of the lead sheathing of the cable by the 10 relatively sharp edges of the hanger, and are usually made of steel having a galvanized finish of aluminum.

Due, however, to the torque action which is described in my Patent No. 2,106,006, it has been 15 found that such saddles, although they delay the cutting of the cable, do not prevent such cutting. Hangers, as disclosed in my aforesaid patent, prevent cable cutting, but are relatively expensive to manufacture, involving as they do the use of a 20 yoke which is assembled with a ring.

The present invention, accordingly, has as its primary object the provision of a saddle which may be employed in conjunction with standard hangers of the character disclosed in the aforesaid Brenizer patents, which will prevent or substantially minimize the cutting of the cables, and which, moreover, are relatively inexpensive to 25 manufacture.

Another object of the invention is to provide 30 a saddle of the character described, the use of which will substantially obviate electrolytic action which is detrimental to the supported cable.

A further object of the invention is to provide 35 a saddle which is of an electrically-insulative character.

A still further object of the invention is to 40 provide a saddle of the character described, which is self-orienting and which is designed to facilitate the discharge therefrom of water which accumulates thereon.

To the accomplishment of the foregoing and 45 related ends, said invention, then, consists of the means hereinafter fully described and particularly pointed out in the claims.

The annexed drawing and the following 50 description set forth in detail certain mechanism embodying the invention, such disclosed means constituting, however, but one of various mechanical forms in which the principle of the invention may be used.

In said annexed drawing:

Fig. 1 is a transverse section through a messenger wire provided with a hanger and a saddle embodying the invention, showing by dot and dash 55 lines the position of the cable upon the saddle;

Fig. 2 is a side view of the parts shown in Fig. 1; Fig. 3 is a top plan view of the parts shown in Fig. 2;

Fig. 4 is a cross-sectional view, taken on the line 4—4 of Fig. 1; and

Fig. 5 is a view similar to Fig. 1, but showing a somewhat modified form of saddle.

Referring more particularly to Figs. 1 to 4, inclusive, 2 designates the messenger wire, 3 the cable hanger, 4 the cable supporting saddle and 10 5 the cable.

The hanger 3 is in the form of suitable wire, 15 preferably galvanized, and includes a cable receiving loop 6 having a bottom portion 7 and upwardly extending side portions 8.

The upper end portions of the side portions 8 of the loop are connected to the messenger wire 2 by means of hooks 10 and 11 which are formed on the respective upper end portions of the side portions 8 of the hanger loop 6, and which are 20 constructed and applied to the messenger wire 2 to connect the hanger thereto and to prevent displacement of the hanger relatively to the messenger wire.

The lower portion of the loop 6, i. e., the portion thereof which receives the saddle 4 extends transversely to the messenger wire 2 and cable 5. The side portions 8 of the loop 6 are bent forming shoulders 9 immediately above the upper ends of the side portions of the saddle 4, and the side 30 portions 8 of the hanger diverge above the shoulders 9 from the plane of the lower portion of the loop 6 to properly space the hooks 10 and 11 longitudinally of the messenger wire, as shown in Figs. 2 and 3.

The cable supporting saddle is generally U-shaped, as seen in Fig. 1, for the reception of the cable 5 and to conform generally to the lower portion of the hanger loop 6, and the saddle comprises a bottom portion 12 and upwardly extending side portions 13. The saddle is further provided with two laterally spaced flanges 14 which form a channel for the reception of the lower portion of the hanger loop 6, the term "laterally," as here used, meaning the direction lengthwise of 45 the messenger wire 2 and the cable 5. The flanges 14 are spaced apart a distance but slightly greater than the width of the wire from which the hanger is formed, so that the saddle is not displaceable relatively to the hanger to any appreciable extent in a direction lengthwise of the messenger wire 2.

The lower portion 12 of the saddle 4 rests upon the lower portion 7 of the hanger loop 6, and, in order to minimize friction between the 50 55

cable and the saddle as well as to facilitate drawing of the cable through the saddle, the upper surface 15 of the lower portion 12 and the inner surfaces 16 of the side portions 13 of the saddle are transversely crowned or rounded, so as to provide, in effect, a point contact of the saddle with the cable.

The flanges 14 are extended downwardly at their lower central portions to provide points 17, 10 which function as drip points to facilitate drainage of water from the saddles. These points, by lowering the center of gravity of the saddle, enables the saddle to become self-orienting in the hanger, the saddle being freely rotatable within the hanger to a slight extent. 15

The base of the groove in the upstanding legs of the U-shaped saddle is so formed with reference to the loop that it is spaced substantially from the loop in order that the saddle may be 20 free to rock therein.

Of prime importance is the fact that the saddle is made from non-metallic material, preferably from thoroughly vitrified homogeneous white porcelain, the surfaces of which have been 25 smoothly covered with a colorless glaze. Other non-metallic materials, such as glass or molded plastics may also be employed for the saddles. Saddles made of glazed porcelain are particularly desirable in that by their use, electrolytic 30 action, which would be detrimental to the supported cable, is obviated. Moreover, by using such non-metallic materials, the saddles are electrically-insulative in character, and in actual practice, it has been found that the saddles may 35 be used to support a non-lead sheath power cable which had to be insulated from the hangers and messenger wire.

Another advantage in using a saddle of glazed porcelain is that the saddle is virtually self-cleaning, rain water readily washing any accumulated dust or dirt from the smooth glazed surface. 40

In that form of the saddle shown in Fig. 5, the surface 15' of the saddle is in the form of an arc having as its center the axis of support of the hanger, that is, the axis of the messenger wire 5. In this way, when the messenger wire swings laterally between its points of support, the cable will not roll up the sides of the saddle, and abrasion of the cable sheathing will be further minimized, as set forth in my aforesaid patent.

Other modes of applying the principle of my 10 invention may be employed instead of the one explained, change being made as regards the mechanism herein disclosed, provided the means stated by any of the following claims or the equivalent of such stated means be employed. 15

I therefore particularly point out and distinctly claim as my invention:

1. In combination, a cable hanger provided with a loop and a U-shaped saddle within the loop, said saddle having laterally spaced flanges 20 to provide a groove therebetween to receive said loop, said groove being slightly wider than the portion of the loop lying therein, whereby the saddle may rotate freely in the loop, the base of the groove on the legs of the saddle being substantially spaced from the loop to provide for 25 rocking of the saddle in the loop.

2. In combination, a cable hanger provided with a loop and a U-shaped saddle within the 30 loop, said saddle having laterally spaced flanges to provide a groove therebetween to receive said loop, said groove being slightly wider than the portion of the loop lying therein, whereby the saddle may rotate freely in the loop, the base of the groove on the legs of the saddle being substantially spaced from the loop to provide for 35 rocking of the saddle in the loop, said saddle having a lower portion of substantial length in the form of an arc having its center the axis of suspension of said hanger. 40

CHARLES H. KLEIN.
